UNITED STATES PATENT OFFICE.

ROLLIN D. FILDES, OF MEDINA, OHIO, ASSIGNOR TO THE MEDINA MANUFACTURING COMPANY, OF MEDINA, OHIO, A CORPORATION OF OHIO.

LIFTING JACK.

Application filed January 3, 1922. Serial No. 526,740.

My invention relates to extension lifting jacks in which the body or pedestal of the jack is made extensible so that the jack is adapted to be used as either a short or a tall jack. In this type of lifting jack the pedestal is made so that it may be shortened or lengthened to suit the available head room where the jack is to be used, the extensible pedestal providing a substantial support for the lifting screw which may be made smaller and lighter on account of the reinforcement provided by the extensible pedestal than would be possible in a tall jack if an extensible pedestal were not used. Among the objects of my invention are the provision of an improved lifting jack having an extensible pedestal; the provision of an improved lifting jack operated by a worm and worm wheel; the provision of a lifting jack having an extensible pedestal made of unfinished parts; the provision of an extensible lifting jack the height of the pedestal of which can be readily changed when not supporting a weight but which cannot be changed when supporting a weight; the provision of a lifting jack having an extensible pedestal which is self lowering when the jack is not supporting a weight but which is automatically locked in adjusted position and prevented from accidental lowering when supporting a weight; the provision of a lifting jack operable by rotary movement of a shaft; and the provision of an extensible folding brace adapted to be used for positioning the jack under the object to be lifted from a point away from the object and for operating the jack from such a point. These and other objects are accomplished by the use of my invention, described in the following specifications and shown in the accompanying drawings in which:—

Fig. 1 is a side elevation partly in section of a lifting jack embodying my invention;

Fig. 2 is a top plan view of the jack shown in Fig. 1;

Fig. 3 is a central vertical section on line III—III of Fig. 1;

Fig. 4 is a horizontal section on line IV—IV of Fig. 1;

Fig. 5 is a horizontal section on line V—V of Fig. 1;

Fig. 6 is a horizontal section on line VI—VI of Fig. 1;

Fig. 7 is a fragmentary view of an automobile showing the application of my lifting jack with the positioning and cranking brace connected to it for raising or lowering the rear axle of the automobile;

Fig. 8 shows my improved extensible cranking brace folded to permit it to be conveniently carried in the tool box of an automobile;

Fig. 9 is a fragmentary view of a joint of my positioning and cranking brace showing the locking sleeve in unlocked position;

Fig. 10 is a fragmentary side view of a joint of my positioning and cranking brace showing the locking sleeve in locking position;

Fig. 11 is a fragmentary side view of the joint shown in Figs. 9 and 10 with the joint unlocked and partly bent;

Fig. 12 is a section on line XII—XII of Fig. 10;

Fig. 13 is a fragmentary view of the operating socket end of my cranking brace; and

Fig. 14 is a section on line XIV—XIV of Fig. 13.

Referring to the drawings, 1 is the lower or base portion of the pedestal, which has a foot or flange, 1^a, preferably cast or otherwise made integral with the upstanding portion, 1^b, of the pedestal.

The upstanding portion, 1^b, of the pedestal is preferably made cylindrical, or in the form of a gradually tapered cone the latter being the form shown in the drawings. I prefer to make the pedestal base, 1, of cast metal. Ribs, 2, or other suitable means may be provided for strengthening the foot flange, 1^a. The pedestal base is made hollow, the aperture, 3, which is preferably formed by a core being somewhat contracted at the upper end of the pedestal base to provide metal for the internal screw threads, 4, which are preferably cast in the metal. For making accurate castings I prefer to provide a core print at the bottom of the pedestal base which will cast a core-cleaning hole, 5, in the foot, 1^a, and provide a convenient means for cleaning the core sand out of the aperture, 3. A metal disc may be pressed or riveted into the core hole, 5, to prevent dirt and water from entering aperture, 3, from the bottom.

The upper portion, 6, of the pedestal is provided with an externally threaded shank,

7, preferably of cast metal having formed upon it, preferably by casting, a screw thread, 8, which is adapted to fit the internal screw threads, 4, formed in the upper portion of the aperture, 3, of the pedestal base, 1. At its top, 9, the upper portion, 6, of the pedestal is enlarged and has a chamber or chambers adapted to receive the operating worm and worm wheel or jack-screw 10 nut which members will be more fully described. The upper portion, 6, of the pedestal also has a longitudinal aperture extending through it to receive the jack-screw, 10. The lower part, 11, of this jack-screw receiving aperture in the member, 6, is preferably made considerably larger in diameter than the diameter of screw, 10, while the upper part, 12, of the aperture is made only large enough in diameter to provide a free sliding fit for the jack-screw, 10. The wall of the contracted portion, 12, of the aperture serves as a guide and support for the jack-screw, 10. The enlarged portion, 11, serves as a grease chamber and also reduces the weight of the pedestal. A metal disc, 11^a, may be secured in the lower end of the shank, 7, to close aperture, 11, for retaining grease or oil therein.

In the top or head, 9, of the upper portion of the pedestal the longitudinal aperture is enlarged into a chamber, 13, for the reception of an anti-friction thrust bearing, such as the ball bearing shown at 14, and the revoluble jack-screw nut, 15. The nut, 15, is threaded upon the jack-screw, 10, and is supported on the pedestal preferably by the bearing, 14. Opening out of chamber, 13, is a recess, 16, adapted to receive the operating worm, 17, the thread of which meshes with worm wheel teeth, 18, upon the periphery of jack-screw nut, 15, for rotating the latter to cause the raising or lowering of jack-screw, 10.

The top or head, 9, of the extensible portion, 6, of the pedestal is preferably provided with a projection, 19, which incloses the recess, 16, and which forms an oil tight housing surrounding the worm, 17.

The worm, 17, is preferably of cast metal and is mounted upon the operating shaft, 20, to which it is secured by any suitable means such as the pin, 21. A top cover or closure, 22, for the chamber, 13, is preferably provided. It may be secured to the head, 9, by any suitable means such as the screws, 23. The cover, 22, has a hole in it through which the jack-screw, 10, slides in its vertical movements. The cover, 22, serves not only to retain lubricant in the chamber, 13, but also retains the jack-screw, 10, and nut, 15, in the pedestal after the parts are assembled. The chambers, 11 and 13, are preferably made large so as to contain enough lubricant to last a long time.

A suitable, load-engaging head, 24, may

be formed upon or secured to the jack-screw, 10. Suitable means may be provided for preventing the screw, 10, from turning with nut, 15, this means being preferably a projection, 25, on jack-screw, 10. This may be any suitable, key-like projection, but I prefer that it be the end of a pin carried in a transverse aperture in screw, 10, near its lower end, and projecting outwardly beyond the side of the screw into a suitable vertical guide-way, 26, formed in the inner wall of the hollow shank, 7, between ribs, 27, preferably cast thereon. In the drawings, pin, 25, is shown extending clear through the screw, 10, forming projections 80 on either side thereof and engaging oppositely disposed guide-ways. It will be noted that the guide-ways or slots, 26, extend upward through the contracted portion, 12, of the aperture in the shank, 7, and open 85 into the expanded portion, 13, of this aperture so that the jack-screw, 10, may be readily inserted into the pedestal member, 6. The guide-way, 26, may be said to extend to the top of the pedestal as the wall of the 90 head, 9, is above the load supporting part of the pedestal and forms a chamber for the jack-screw and operating worm. The screw, 10, may be raised until the ends of pin, 25, strike the lower ball race, 28, of 95 the ball bearing, 14, by which the upward movement of the jack-screw, 10, will be arrested. While I prefer to employ an anti-friction thrust-bearing for the nut, 15, it is obvious that, in the absence of such a bearing, the bottom of the nut may serve 100 as a stop to limit the upward movement of the screw, 10.

I prefer to provide a ball retainer, 28^a, preferably a sheet metal stamping, comprising a perforated disc for receiving and separating the balls and internal and external oppositely upset flanges to prevent the disc from being displaced far enough to allow the balls to escape.

The adjustment of the height of the pedestal is accomplished by screwing the shank, 7, of the upper pedestal member, 6, into and out of the pedestal base, 1. When adjusted it may, if desired, be held in the adjusted position by means of the set screw, 29, shown in Fig. 3. I prefer to make the pitch of the threads, 8, so coarse that the shank, 7, will be self lowering, or nearly so, when the set screw, 29, is loosened and when the jack is free. Such a coarse pitched thread facilitates the rapid adjustment of the height of the pedestal. When, however, the jack is supporting a weight the head, 24, of screw, 10, is in firm engagement with the load while the foot flange, 1^a, of the pedestal, 1, is in firm engagement with the ground and the shank, 7, is thereby locked and prevented from rotating in the pedestal base, 1. In other words my extensible ped-

estal is automatically held or locked in adjusted position when the jack is supporting a weight and cannot be accidentally or suddenly lowered.

5 The worm, 17, is preferably cast, or, made of a drop-forging, and has its axis inclined to the axis of the worm wheel, 15. This makes it possible to form the teeth, 18, of the worm wheel, parallel with its axis 10 which facilitates the forming of the teeth regardless of whether they be cast, drop-forged or cut. Inclining the axis of the worm, 17, also assists in placing and operating the jack in inaccessible positions such 15 as that shown in Fig. 7, where, it will be noted, the shank, 30, of the cranking brace, 31, which is a detachable extension of shaft, 20, is shown inclined upwardly from the jack and extended back behind the vehicle 20 where it can be readily manipulated.

To hold the worm, 17, against end thrusts when the jack is being operated to lift a load, I prefer to provide an anti-friction step or thrust bearing such as the hardened 25 steel ball shown at 20^a, between the end of the shaft, 20, and the bottom of hole, 35, in which the shaft is mounted. The hub of the worm, 17, may be made slightly shorter than the recess, 16, to prevent frictional contact on the hub when lifting a 30 load. When lowering a load the end thrust of the worm, 17, is so small as to make it unnecessary to provide an anti-friction bearing at the other end of the worm.

35 In the manufacture of my invention I prefer to make all of the parts, 1, 6, 15 and 17, of cast metal, preferably of gray or malleable cast iron, as I find that these parts can be made sufficiently accurate by 40 casting to require very little machine finishing. In fact, the only machine work that I have found necessary upon these parts as shown in the accompanying drawings is the drilling and tapping of the hole in the 45 pedestal, 1, to receive the set screw, 29, the facing of the seat, 33, for supporting the lower race, 28, of the ball bearing, 14, the facing of the surface, 34, for receiving the cover plate or closure, 22, the drilling of 50 the hole, 35, for receiving the operating shaft, 20, and the facing of the lower end, 36, of nut, 15, where it is supported by the upper ball race, 37, of the thrust bearing, 14. It is obvious that instead of the ball 55 bearing, 14, any other anti-friction bearing such as anti-friction washers or other form of thrust bearing may be employed. I have found, however, that a ball bearing such as shown in the drawings operates satisfactorily in this structure.

For operating the shaft, 20, I prefer to provide a drive pin, key or similar projection such as shown at 38, which is adapted to engage with a socket wrench or other 60 operating sleeve which can be slipped over

the end of shaft, 20. It is obvious that the shaft, 20, may be provided with a square or other flat sided end which would answer the same purpose. The projection, 38, also serves to detachably secure the cranking 70 brace to the jack so that the latter may be readily positioned.

As the lifting jack, especially when used for raising the axle of an automobile, has to be set in somewhat inaccessible places, 75 I have provided a folding, positioning and cranking brace, 31, the construction of which will now be described. The end, 39, of the shank of the brace is provided with a socket, 40, which is adapted to fit over the end of shaft, 20. The wall of the socket is provided with a T slot, 41, like the slot of a bayonet-joint, the longitudinal portion of which slot permits the passage of the drive pin, 38, through it into the transverse slot, 80 42. The socket, 40, having been slipped over the end of the shaft, 20, the socket may be rotated about the shaft until the pin, 38, engages the end of the transverse slot, 42, when further rotation of the socket 85 will cause the shaft, 20, and worm, 17, to rotate with it. When the shaft, 20, and socket, 40, are thus engaged the shaft is securely held to the brace shank and the jack may be pushed under the object to be 90 lifted by means of the extension brace thus making it unnecessary for the user to get down under the object to be lifted to set the jack.

The folding, positioning and cranking 100 brace which is shown in the drawing is preferably composed of several joints hinged together by means of metal stampings as shown at 43. The ends of the rod or shank sections, 30, 31 and 44, are preferably somewhat enlarged and provided with transverse pin apertures for receiving the connecting and hinge pins such as those shown at 45 and 46 respectively. One end of each of the stampings, 43, is rigidly connected to 105 a shank section by means of a pin, 45, and by reason of the engagement of the sleeve like portion, 47, of the stamping, 43, with the end of the shank section as shown in Fig. 9.

The other end of the stamping, 43, is hinged to the abutting end of the adjacent shank section so that it can fold only in one direction, the end, 48, of the stamping, 43, preventing the rotation of the hinged 110 shank section in the opposite direction. In other words, I provide "knee" joints between the shank sections. To prevent the flexing of the "knee" joint of the shank when in operation I prefer to provide projections 115 49, upon the ends of the side portion of the stamping, 43, which side portions are spaced far enough apart to permit the hinged shank section to pass between them. I further provide, upon each shank which is 120 125 130

thus hinged to a stamping, 43, a loose sleeve such as shown at 50, the diameter of which is too great to pass between the projections, 49, so that when this sleeve is pushed into the position in which it is seen in Figs. 7 and 10, the knee joints of the shank cannot flex.

While I have shown an offset crank in the operating shank section, 31, it is obvious that any other convenient means for rotating the cranking brace may be employed.

Fig. 12 is a cross section through the brace shank and sleeve, 50, the section being taken on line XIII—XII of Fig. 10 showing the manner in which the sleeve, 50, engages the projections, 49, to prevent the flexing of the joint.

Fig. 14 which is a section on line XIV—XIV of Fig. 13 shows the manner in which I prefer to form the end of the socket member, 40. Instead of cutting the longitudinal slot, 41, clear through the wall of the socket, 40, I prefer to expand the metal outward or otherwise form it so that the slot, 41, will be covered and its walls connected and reinforced by a bridge piece, 51, which greatly strengthens the socket member and enables it to withstand the stresses which are put upon it when in use.

The operation of my invention is as follows:

Assuming that it is desired to lift the axle, 52, of the automobile shown in Fig. 7, the pedestal members, 1 and 6, are adjusted so that with the lifting screw, 10, preferably protruding a little above the top of the pedestal head, 9, the total height of the jack is slightly less than the height of the space available in which to set the jack. This height can readily be judged by the eye of the operator. The set screw, 29, is now preferably tightened to prevent change in the adjustment of the height of the jack while it is being positioned. The socket of the cranking brace is next applied to the shaft, 20, the cranking brace is unfolded and its joints are locked by slipping the sleeves, 50, into the positions in which they are shown in Fig. 7 and the jack is shoved into position under the axle, 52, by means of the extended positioning and operating brace. When thus in position the jack may be raised by rotating the crank member, 31, until the axle, 52, is lifted to the desired height. In this operation of lifting, the pin, 38, is engaged by one end of slot, 42, in the socket, 40, and causes the shaft, 20, to rotate with the brace crank, 31.

To lower the jack the brace crank, 31, is rotated in the opposite direction. When the head, 24, has been lowered sufficiently to be relieved of the weight which it has lifted and to clear the axle, 52, the jack may be pulled out from under the machine. The positioning and operating brace may now be

removed from the shaft, 20, and folded into the position shown in Fig. 8 by sliding the sleeves, 50, out of contact with projections, 49. If it is desired to make the jack as compact as possible for placing it in a tool box, the pedestal of the jack may then be adjusted to its shortest height and the set screw, 29, tightened. The screw, 10, may also be lowered to its lowest position by turning the shaft, 20.

It will be seen that my invention provides a jack which is strong and rigid throughout its full range of use but which may be compacted into a very small space when not in use. My invention is simple and inexpensive to manufacture and possesses many advantageous features which are distinct improvements over other forms of lifting jacks with which I am familiar. For standard automobile work I have made jacks embodying my invention capable of being used throughout a range of height from $8\frac{1}{2}$ " to 18". It is obvious that various other ranges of height can readily be made within the practical limits of construction.

It will be apparent to those skilled in the art that modifications may be made in my invention without departing from the scope thereof.

I claim:

1. In a lifting jack, a pedestal member, a jack-screw mounted to be moved up and down on said pedestal, said pedestal having an enlarged hollow head at one end, a grease-receptacle at its opposite end of greater diameter than said jack-screw, and a bore connecting said grease-receptacle and the hollow portion of said pedestal of a diameter to provide a free sliding fit for the jack-screw, said bore having a vertical internal guideway extending its full length, and said grease-receptacle having vertical ribs the space between which forms a continuation of said vertical internal guideway in the bore, a projection on the lower end of said jack-screw adapted to travel up and down in the guideway and between the ribs to prevent the turning of the jack-screw, and means mounted in the hollow head for operating the jack-screw.

2. A lifting jack embodying a tubular base member and a tubular extension longitudinally adjustable with respect thereto, said tubular extension being formed with an enlarged hollow head at its upper end and having its lower portion internally enlarged and provided with a closed bottom to form a grease-receptacle, operating mechanism including a worm-gear located in said enlarged hollow head, and a jack-screw mounted in said worm-gear and movable up and down in said grease-receptacle.

3. A lifting jack embodying a tubular base member and a tubular extension longitudinally adjustable with respect thereto,

said tubular extension being formed with an enlarged hollow head at its upper end and having its lower portion interiorly enlarged and provided with a closed bottom to form a grease-receptacle, operating mechanism including a worm-gear located in said enlarged hollow head, a jack-screw mounted

in said worm-gear and movable up and down in said grease-receptacle, and a locking means projecting exteriorly from said base 10 for locking the tubular extension in any adjusted positions relative thereto.

In testimony whereof I affix my signature.

ROLLIN D. FILDES.
